[54] **ELECTROSTATOGRAPHIC LIGHT SENSITIZED DRUM CLEANING ARRANGEMENT IN WET-TYPE DEVELOPMENT**
1 Claim, 1 Drawing Fig.
[52] U.S. Cl..... 355/15,
355/3

ABSTRACT: An electrostographic light sensitized drum cleaning arrangement in wet-type development process wherein a latent image is removed by pressing a rotary body against the surface of the drum whose one portion is immersed in a developing solution.

**ELECTROSTATOGRAPHIC LIGHT SENSITIZED DRUM
CLEANING ARRANGEMENT IN WET-TYPE
DEVELOPMENT**

BACKGROUND OF THE INVENTION

The present invention relates to an electrostatographic light sensitized drum cleaning arrangement and more particularly an improved arrangement for cleaning an electrostatographic light sensitized drum for wet-type development.

It is well known in electrostatography to have a photoconductive layer imparted with an electrostatic charge. The layer is then exposed so as to form an electrostatic latent image, and the image is developed by a liquid developing agent. The developed image is then transferred to a suitable record support such as a paper sheet. In this case, it is an important problem to thoroughly clean the drum which includes the photoconductive layer in order to make good quality copies, but so far no satisfactory cleaning arrangement has been proposed.

SUMMARY OF THE INVENTION

In brief, the present invention provides an arrangement for cleaning an electrostatographic light sensitized drum for use in wet-type development comprising the step of pressing a rotary brush against the surface of said drum which is disposed so as to have its one portion immersed in a developing solution, thereby cleaning thoroughly the surface of the drum and solving the aforementioned problem.

BRIEF DESCRIPTION OF THE DRAWING

The single FIGURE illustrates one preferred embodiment according to the present invention.

DESCRIPTION OF THE PREFERRED EMBODIMENT

Referring to the single FIGURE a drum 3 has an electrically conductive support 2 and a photoconductive layer 1 formed thereupon. The drum 3 is arranged in such a manner that one portion of the drum 3 is always immersed in a processing solution or developing solution 4 within a developing solution chamber 5. A recording support 6 such as a paper sheet is provided in contact with the surface of the drum 3, which is the photoconductive layer 1, and this contact is maintained by an image transfer electrode 7 disposed on the other side of the recording support 6. A rotary brush 8 is disposed within the

45

developing solution 4 in such a manner that the brush 8 may be pressed against the drum 3 or removed away therefrom. Reference numeral 10 designates an optical system for forming an electrostatic latent image upon the surface of the 5 photoconductive layer 1.

When the toner particles remain upon the surface of the photoconductive layer 1 after the image has been transferred to the recording support 6. These particles can be easily separated from the surface of the drum when immersed in the developing solution 4 and removed therefrom into the solution by means of the rotary brush 8. It is preferable to position the rotary brush 8 so as to contact the lowermost portion of the drum 3 within the solution 4 for attaining the best result.

According to the present invention, the toner consumption 15 can be minimized and the drum can be thoroughly cleaned from the remaining toner particles as compared with the case in which the remaining particles are cleaned off from the drum at the exterior of the developing solution by means of a brush.

I claim:

- 20 1. An electrostatographic light sensitized drum cleaning arrangement in wet-type developing comprising
an open chamber having developing solution containing
particles therein;
an electrostatographic light sensitized rotatable drum having
part thereof immersed in said developing solution;
said drum having a photoconductive layer formed thereon;
an optical system adapted to form an electrostatic latent
image upon said layer, said optical system spaced from
said drum in a location opposite to the immersed part of
said drum;
- 25 a recording support having recording paper thereon positioned in rotatable contact with said layer, said recording support located between said optical system and said immersed part of said drum;
a lever;
- 30 a brush mounted for rotation at one end of said lever, said
brush and lever being completely immersed in the
developing solution in said chamber, the other end of said
lever mounted in pivoting relation on the side of said
chamber; and
- 35 said lever being pivotable to selectively move said brush
into and out of particle cleaning contact with a portion of
said layer that has been rotated to be immersed after
passing said optical system and said recording support.

UNITED STATES PATENT OFFICE
CERTIFICATE OF CORRECTION

Patent No. 3,622,237 Dated November 23, 1971

Inventor(x) Bernt Fried Walther von Grabe

It is certified that error appears in the above-identified patent and that said Letters Patent are hereby corrected as shown below:

Correct name of inventor to read:

-- Bernt Fried Walther von Grabe --;

Column 2, line 6, replace "When the" by -- The --.

Signed and sealed this 2nd day of May 1972.
